UNITED STATES PATENT OFFICE

ROSE LANDRUM, OF EL PASO, TEXAS

HAIR CURLING DEVICE

Application filed November 5, 1930. Serial No. 493,653.

My present invention has reference to a new and novel device for curling hair, and my object is the provision of a device for this purpose which is characterized by simplicity in construction, cheapness in manufacture and thoroughness in efficiency.

A further object is the provision of an electrically heated device for this purpose which may be securely clamped on the head, which cannot inflict injury to the person operated upon, which permits strands of hair being oppositely wound in ∞ formation, which does not require finger waving or set or drying, as such drying is effected when the steaming operation is completed, and wherein after the hair is combed in place in a wave, a flat permanent Marcel wave will be produced.

To the attainment of the foregoing the invention consists in the improvement herein-after described and definitely claimed.

In the drawing:

Figure 1 is a top plan view of my improvement.

Figure 2 is a side elevation thereof.

Figure 3 is a transverse sectional view approximately on the line 3—3 of Figure 2.

Figure 4 is an end view of the improvement.

The base 1 of the improvement comprises two similar substantially rectangular blocks of insulated material. The blocks at their confronting ends are provided with interengaging tongues and grooves which are substantially V-shaped, the tongue in one of the blocks being indicated by the numeral 2 and the groove in the cooperating block by the numeral 3. The blocks at one of their ends are pivotally connected, as at 4, and the under faces of the blocks have adhesively or otherwise fixedly secured thereon strips 5 of compressible material.

The pivots 4 are in the nature of bolts and are disposed a suitable distance from the confronting ends of the blocks 1 and these pivots secure on the upper face of the blocks the face of a substantially U-shaped member or yoke. The right angular upwardly directed ends 6 of the device have secured thereon a shaft 7 and there is journaled on the shaft

7 the flat ends 8 of cross sectionally rounded rods 9 that afford shafts. Each of the shafts has removably journaled thereon a cylindrical curling member 10. The base blocks 1 below and adjacent to the outer ends 55 of the curling cylinders 10 have fixed thereon plates 11 and 12, respectively. The plates 12 have pivotally secured to their upper faces clips or clamps 13 to engage with the ends of the shafts 9 that project beyond the curling cylinders 10 which the outer ends of the top of the plates 12 are extended upwardly, as at 14, the outer edges of the said extensions being beveled or inclined inwardly from the base to the top of the said flanges 65 or extensions, as indicated for distinction by the numeral 15. The confronting faces of the extensions are straight and designed for contacting engagement with each other. These extensions provide spacer elements and 70 are designed to be received between the shafts 9. Similar but angularly arranged flanges 15' are formed on the ends of the plate 11. These flanges also provide spacer elements. The spacer elements 14 have their outer 75 angle edges disposed between the parts 8 of the shafts.

The inner sides of the plate 12 may have angle extensions 16 to contact with the outer sides of the blocks 1 to more effectively 80 strengthen the spacer plates 14, while the ends of the blocks 1, outward of the spacer members 14 are provided respectively with a pair of ears 16 and with a notched plate 17. There is pivoted between the ears the end of a lock 85 rod 18 the outer end of the lock rod being flanged and being engaged by a milled nut 19 which is screwed against the notched plate 17 when the rod is received in the notch of the said plate and whereby the blocks, when 90 swung together to grip a portion of the hair of the person operated upon may be locked as may likewise the spacer elements and the curling rods arranged in longitudinal alinement. 95

In operation the blocks 1 are swung away from each other on their pivots and are arranged against the head of the person being operated on. The blocks are then swung toward each other so that the interengaging tongues and grooves of the fibre base blocks 100

will, when the blocks are locked against each other firmly grip the said strands of hair. The latching elements 13 are released so that the shafts 9 may be swung upwardly to permit of the curling cylinders being removed from the shafts. The gripped strands of hair are wound in opposite directions around the respective cylinders 10, are arranged upon the shafts and further wound thereon. The 10 shafts, when moved toward the base blocks 1 will contact with the outer angle edges of the spaced members 14' and 15' and thus forcing the said shafts and the curling cylinders with the curled hair thereon away from 15 each other and thereby stretch the hair on the cylinders. Current is applied to the shafts for heating the curling cylinders and thus effect a curling action upon the hair. The improvement does not require finger 20 waving or set or drying as the hair will be dried as soon as the steaming operation is completed. The hair is combed and placed as a marcel wave.

Having described the invention, I claim:

25 1. A hair curling device of the type described, two fibre spaced blocks having the confronting ends provided with spaced tongues and grooves, a substantially U-shaped bracket arranged on the blocks on one 30 end thereof and to which bracket the blocks are pivoted, a transverse shaft carried by the bracket, longitudinal shafts journaled on the transverse shaft, means carried by the blocks for clamping the outer ends of the longitudinal 35 shafts, curling cylinders removably journaled on the longitudinal shafts, spacer members carried by each of the blocks and designed for contacting engagement and to contact with and spread the longitudinal 40 shafts when said shafts are brought thereagainst, and swingable means for locking the blocks together.

2. A hair curling device of the class described comprising two blocks of insulating 45 material having compressible pads on the outer faces thereof, the blocks having their confronting ends provided with interengaging tongues and grooves, a U-shaped bracket disposed over the blocks at one end thereof, 50 pivot elements for the blocks securing the bracket thereon, a transverse shaft fixed on the bracket, longitudinal shafts having one of their ends journaled on the transverse shaft, curling cylinders removably journaled 55 on the longitudinal shafts, spaced pairs of plates on the blocks, pivotally supported spring clamps on one of the plates to engage the outer ends of the longitudinal shafts, said plates having angle extensions whose outer 60 edges are cut angularly and which provide spacers to be received between the confronting sides of the longitudinal shafts, and to force 65 said shaft away from each other, spaced ears on the end of one of the blocks, a notched plate on the end of the second block, a lock 70

bolt pivotally secured between the ears and swingable into the notched plate and a knurled nut threaded on the bolt to engage with the notched plate for holding the blocks against each other.

In testimony whereof I affix my signature.

ROSE LANDRUM.
